UNITED STATES PATENT OFFICE.

ABNER M. ROSEBRUGH, OF TORONTO, ONTARIO, CANADA.

GALVANIC BATTERY.

SPECIFICATION forming part of Letters Patent No. 271,692, dated February 6, 1883.

Application filed May 27, 1882. (No model.)

To all whom it may concern:

Be it known that I, ABNER MULHOLLAND ROSEBRUGH, of the city of Toronto, county of York, Province of Ontario, Canada, a subject 5 of the Queen of Great Britain, have invented certain new and useful Improvements in Galvanic Batteries, of which the following is a specification.

This invention relates more particularly to 10 improvements in that form of portable galvanic batteries in which the elements are attached to the hydrostat-plate, and in which are provided empty drip-cups for the elements to be suspended in when the battery is not in 15 action. In batteries of this description there are two principal defects, namely: first, in the means used to effect the pressure on the hydrostat-plate, which is both complicate and inconvenient; and, second, in being obliged, 20 in immersing and replacing the elements, to rotate them upon their horizontal axes, which causes more or less dripping of the fluid.

The object of this invention is, first, to arrange the hydrostat so that the desired pressure upon said hydrostat shall be automatic; 25 second, to arrange the parts so that the elements may be immersed in the battery-fluid and replaced in the drip-cups without any reversal of their position, and without causing 30 any dripping; third, to provide for better protection of the bottom of the case; and, fourth, the introduction of certain other modifications with a view of making medical batteries more convenient and useful.

35 In the accompanying drawings, Figure 1 represents the battery open, with the elements in the drip-cups, and showing part of the lid. Fig. 2 is a section, partly diagrammatic, of the same on or near the line *a b*; and Fig. 3 is 40 a longitudinal section on the line *c d*. Fig. 4 represents the battery open and the elements immersed in the battery-fluid. Fig. 5 is a vertical section of Fig. 4, partly diagrammatic, on or near the line *e f*. Fig. 6 is a modification 45 of Fig. 2.

Like letters refer to like parts.

A A' A² A³ are horizontal sections or hydrostat-plates; B B' B², empty or drip cells; C C' C², battery-fluid cells; D D' D², exciting 50 elements; E, induction-coil; F F' F², handles for lifting the horizontal sections; H I, primary-wire faradic-battery connections; H' I',

elements for faradic battery; J, battery-case; K, lid of battery-case; O, elastic cushions or overlapping cleats; M, bearing of said cushions; N, cleats for keeping cells in position; L, elastic supports for cells; G, supplemental screw-cup for making connection with elements of adjoining section. 55

The action of the automatic hydrostat is as 60 follows: The size and depth of the case and the size of the cells and hydrostat-plate are so adjusted that when the lid is closed firm pressure is exerted by the overlapping part of the lid, cleat, or cushion O against the ends 65 of the hydrostat-plates at M and M'. This pressure compresses the elastic lining of the hydrostat-plate against the top of the cells. When the battery-case is closed, therefore, the battery-cells are automatically sealed watertight, and the apparatus is ready for transportation. 70 The elastic supports L give additional elasticity to the hydrostat.

The overlapping portion of the lid O may 75 be a yielding cushion—as, for instance, soft india-rubber or cork. It may be a cleat secured to the side of the box-lid, or the sides of the lid may be made to overlap the hydrostat-plates by being made of thicker material.

The elastic support or supports beneath the 80 cells L may consist of two bands of soft india-rubber or similar material extending the length of the inside of the case, beneath the ends of the cells; or the entire inside bottom of the box 85 may be lined with soft india-rubber cloth or any similar material that will both give elastic support to the cells and resist the action of the battery-fluid. The depth of the box is such that one or more layers of india-rubber cloth or one or more layers of bibulous paper 90 may be placed beneath the cells, so as to give delicate adjustment to the hydrostat.

The apparatus is operated as follows: In putting the battery in action the section or plate A² is removed, so as to make room for 95 the overlapping hydrostat-plate of section A', the elements connected with which (1 2 3 4 5 6) are simply elevated from the drip-cup B' and immersed in the cells C'. In the same manner the elements of the next section (12 11 10 100 9 8 7) are immersed in the battery-cells C, space being made for the overlapping hydrostat-plate by the removal of section A'. The elements of both sections being immersed, they

are connected at the ends next to the hinged cover by a coupling wire or spring connecting the post 6, or the last post of one series, with the post $6\frac{1}{2}$, or the first post of the next series, 5 the supplemental post G and its bar G' rendering necessary only a very short connecting wire or spring. When three or more series of cells are used the third series is connected at the opposite end—as, for instance, opposite No. 10 12, the supplemental connecting-post being connected with No. $12\frac{1}{2}$ post of the next series, and so on.

In constructing a battery with a large number of cells it may be convenient to have a 15 larger number of cells in each section—nine, for instance, instead of six—and arranged as follows: 1 to 9, 10 to 18, 19 to 27, and so on. In the latter case the supplemented posts G would be attached to $9\frac{1}{2}$ of the second series and $18\frac{1}{2}$ 20 of the third, $9\frac{1}{2}$ being at the distant end of the second series and $18\frac{1}{2}$ at the near side of third series.

In securing the elements to the hydrostat-plates, if the first element is a positive element, 25 the last element of that series would be a negative element, and the first of the next series would be positive and the last negative, and so on. Thus, if carbon is attached to post $\frac{1}{2}$ and zinc to post 6, carbon would be attached 30 to $6\frac{1}{2}$ and zinc to 12. Consequently, when the elements are immersed in the battery-fluid, retaining the same relative position, and 6 and $6\frac{1}{2}$ being connected, the post $\frac{1}{2}$ would be the positive pole and post 12 would be the negative.

35 A supplemental post, G, is used for the purpose of shortening the distance for connecting the last element of one series with the first of the next. It has connection with the first screw-post, preferably, by means of a metallic 40 band. It is connected with the first screw-post of each series, except that of the first series.

An essential part of this invention is the provision for the overlapping of the hydrostat- 45 plate when the first series of cells, A', is immersed. When an extra battery-cell is provided for the faradic coil, as represented in the drawings, c³, the hydrostat-plate of A' covers it when the elements are immersed. In 50 this case an additional space is provided for a drip-cup, B³, by lengthening the inside of the case to that extent. To save this space, however, provision may be made for the drip-cup in the inside of the lid; but in cases where no 55 extra battery-cell is provided for the faradic coil this space is utilized for the extra drip-cup, as represented in Fig. 6, B².

In this battery, as described, the series of elements are represented as being divided into 60 separate sections, or attached to separate hydrostat-plates. This arrangement is not absolutely necessary, and for some purposes it is more convenient to have the sections all in one piece. All the connections being permanent,

the use of connecting-wires is unnecessary, 65 and, moreover, with such an arrangement it is easier to attach a pole-changer, current-selector, galvanometer, &c.

When the battery contains a large number of elements I propose to use two cases, one 70 containing the battery-cells, and the other case containing, say, one large drip-cell. I would place the battery-cells side by side, without any intervening space or drip-cell. The elements would be arranged in close rank to correspond with the position of the cells, and preferably all attached to the same section. I propose using two cases for convenience of transportation. A separate hydrostat-plate is provided, to which, for convenience, an in- 80 duction-coil may be attached. In smaller batteries the drip-cup may be arranged in the same case as the battery-cell.

I am aware of the fact that it is not new to hold the hydrostat-plate down upon the tops 85 of the cells by a presser-foot, rod, and screw acting independently of the cover or lid, and I do not claim such arrangement.

What I claim as new is—

1. A galvanic battery composed of a case, 90 a series of cells within the same, a set of removable hydrostat-plates carrying the elements and resting upon the tops of the cells, and a hinged lid or cover for closing in the case, having bearing-surfaces for pressing 95 against the tops of the hydrostat-plates when closed and forcing them into a sealed joint with the cells, as described.

2. A galvanic battery composed of alternating drip-cells and exciting-cells, a set of 100 hydrostat-plates made of a width to cover two series of cells, and having the elements attached to the under side of the same, near one edge, and a case made of greater length than all the hydrostat-plates for permitting the lateral adjustment of the hydrostat-plates from the filled cells to the empty cells, or vice versa, without turning the plates, as described.

3. The combination, in a galvanic battery, 110 of a case having a series of cells, a set of hydrostat-plates resting upon the tops of the cells, elastic supports beneath the cells, and a hinged cover adapted to be closed down upon the hydrostat-plates, substantially as described.

4. The combination, in a galvanic battery, 120 of a case having alternating series of drip-cells and cells filled with exciting-fluid, a set of hydrostat-plates covering two sets of cells, and having underneath a series of elements on one side, and on top a conductor, G', and a post, G, for utilizing a short connection between the elements of one plate and those of the next, as described.

A. M. ROSEBRUGH.
